(57) **CLAIM**

The ornamental design for a controller box, as shown and
described.

DESCRIPTION

FIG. 1 is a perspective view of a controller box showing my
new design;

FIG. 2 is a front view thereof;

FIG. 3 is a rear view thereof;

FIG. 4 is a left side and right side view thereof;

FIG. 5 is a top view thereof;

FIG. 6 is a bottom view thereof; and,

FIG. 7 is another perspective view showing the controller
box.

The broken line environmental showing is for illustrative
purpose only and forms no part of the claimed design.
